VACUUM PUMP SUCTION CONTROL

Daniel B. Banks, Drexel Hill, Pa., assignor to Sun Oil Company, Philadelphia, Pa., a corporation of New Jersey

Application November 13, 1948, Serial No. 59,808

5 Claims. (Cl. 230—4)

1

This invention relates to compressors, and especially to regulating devices to be connected to compressors for exhausting systems requiring vacuum conditions for operation.

An object of the invention is to disclose a method and apparatus for unloading a suction compressor during the starting-up operation.

It has been found that the "start-up" on systems requiring high vacuum or greatly reduced pressures, place an initial burden on the compressor far in excess of the power demands required later in the cycle to maintain these low pressures. Experience shows in the operation of a vacuum pump or compressor on two pounds absolute suction pressure and twenty pounds discharge pressure, the horsepower requirements when reducing suction pressure to nine pounds absolute are approximately 200% higher at this point than they are at the final reduction to two pounds absolute.

In the preferred form of this invention the initial unloading of the compressor is attained by circulating the discharge of the compressor back to the suction or intake side until it is brought up to maximum speed and thoroughly warmed. The required reduced pressure is then built up within the compressor after which it is transmitted to the system without undue strain on the driving mechanism. This method and the apparatus used to obtain these results greatly reduces the initial power requirement.

It is, therefore, a further object of this invention to disclose a method of operation and the apparatus for combining the automatic control features used in operation at reduced pressures, with initial unloading required in the economical design and operation of systems presenting such overload problems.

The accompanying drawing illustrating one form which the invention may assume in practice, is a diagrammatic view of a compressor with the unloading and automatic operational control apparatus constructed in accordance with the invention.

Referring more particularly to the drawing, a compressor 10 is shown in which a suction header 11 and a discharge header 12 are designed to coordinate the functions of the operating cylinders generally indicated by the connections to the compressor 10 from the suction and discharge members. The suction line or main 13 of the system 14 is connected to the suction header at 15, while the discharge header 12 is connected to a discharge line or main 16. In the discharge line 16 conveniently arranged in the

2

proximity of the compressor, a manually controlled valve 17 is installed. Connected to the discharge header 12, here shown at the end opposite to the connection with the discharge or exhaust mains 16 but which may be connected at any convenient point to the discharge header 12, the by-pass 18 is shown. A valve 19, manually controlled, is inserted in the by-pass 18 at an easily accessible location. The by-pass 18 is conducted around the compressor to connect at a point 20 with the suction lines of the system. A manually controlled valve 21 is shown between the by-pass connection 20 and the system to permit disengaging the suction compressor, if desired.

As shown, an automatically operated valve 22, which may be of the butterfly type, is inserted in the suction line 13 adjacent the compressor suction header 11 and the connection 20 of the by-pass 18. A diaphragm head 23 for the operation of the valve 22 is shown in the line 24 which, in the disclosed apparatus, is a conduit permitting the transmission of pressures from the recording pressure controller 25. This controller is a commercially available instrument and is, therefore, not detailed in the drawing. It includes gauges G and G' for comparison of pressures. It is connected to the suction side of the compressor for suction operation as at the point 26 by conduit 27. In the conduit 28—24 connecting the pressure controller 25 with the pressure responsive valve 22, a 3-way, 4-port cock 29 is shown with operating lever L, together with the necessary piping arrangement to present a variety of pressure conditions to the valve 22. The conduit 30 is a by-pass to the instrument air source and taps the inlet line 31 of the pressure controller. The conduit 32 is a vent to the atmosphere which permits complete exhaustion of any pressure existing on the valve for facility of operation.

The method of operation and the details of the functions of the apparatus will best be understood if it is remembered that although the automatic control is a necessary adjunct of the operational function of the suction compressor during the maintaining of low pressures on the system, it also plays a very necessary part in the unloading of the compressor during the starting up period. With this in mind, the details of the unloading incidental to start-up of the compressor will be described.

Before starting the compressor, the 3-way, 4-port cock 29 is turned by lever L to connect the pressure controlled valve 22 with the conduit 30

so that it is subjected to the instrument air pressure source in line 31 which, for purposes of illustration, will be considered as 15 pounds gauge pressure. Thus, the pressure of 15 pounds admitted to the valve will hold it open and connect the suction header 11 directly to the suction side of the system to be exhausted. The valve 21 in the suction line, between the system to be exhausted and the connection 20 of bypass 18, is opened, thereby connecting the system to the suction side of the compressor.

The valve 19 in the by-pass 18 is opened whereby the by-pass 18 is connected to the suction lines 14 at the point 20 as previously noted. The valve 17, which is a manually operated device to connect and disconnect the discharge header 12 with the exhaust mains 16, is closed. By adjusting these valves as directed, a path of circulation is established through the compressor, thence through the by-pass to the suction side of the system, which is open to the circulation effect, and then back through the compressor. The circulation from the discharge header 12 through the by-pass 18 to a point in the suction line 20 adjacent the suction header but outside the automatic control valve 22, as noted, greatly reduces the starting load on the compressor by cutting down the discharge load which, without the by-pass 18, would have to be overcome in the starting period.

The pressure controller 25 is now set to the desired reduced pressure at which the system is to operate. In our example, this will be considered as 2 pounds absolute, as previously stated. The engine which operates the compressor is now started and is heated and checked for proper operation. It is then speeded up to the maximum R. P. M. A suction circulation is now established in which the discharge of the compressor is returned to the system suction line adjacent the compressor intake just outside the automatic control valve 22, and the discharge circulation is restricted to the by-pass return and not permitted to exhaust to the discharge mains.

After the compressor is warmed up and running properly the 3-way, 4-port cock 29 is rotated to the valve 22 connection with the exhaust line 32 to remove the 15 pounds air pressure which held it open, and thence to the instrument control position through which direct control is established with the pressure controller 25. As soon as the 15 pounds air pressure is exhausted, the automatic control valve 22 closes rapidly and remains closed until opened by the pressure controller 25 which has been set to operate at 2 pounds absolute. Valve 22 is located adjacent suction header 11 to reduce the volume between it and the suction side of the compressor 10 which affords quick and complete exhaustion in a few strokes of the compressor.

The valve 22 now under the automatic control of the pressure controller will remain closed until the desired 2 pounds absolute pressure, or less, is reached between it and the compressor intake 11. It will be evident that the compressor is now establishing the suction within itself as both the suction lines and the discharge lines of the system are closed. The manually operated valve 19 in the by-pass 18 and the valve 17 connecting the discharge header 12 to the exhaust lines 16 are respectively closed and opened concurrently. The compressor now discharges to the exhaust mains 16. The pressure controller 25 directly connected to the suction side of the compressor is effectively brought into operation and the au-

tomatic valve 22 opens to the system to establish the desired reduced pressure without placing excessive demands on the compressor engine. The valve 22 now being controlled from the suction header 11 through the recording pressure controller 25 maintains the two pounds absolute pressure at the suction of the compressor regardless of the pressure applied at any time up-stream from valve 22. The maintenance of pressure relationship makes it impossible to overload the compressor.

I claim:

1. A fluid pressure reducing device in combination with a reduced pressure system which includes a compressor having suction and discharge conduits, said suction conduit being connected to said system, said device comprising a valve in said suction conduit positioned between said system and said compressor, an automatically operating pressure controller means for actuating said valve, and a conduit connecting said controller means with said suction conduit at a point between said compressor and said valve so that said valve is actuated in accordance with the pressure in said suction conduit between said compressor and said valve.

2. A fluid pressure reducing device in combination with a reduced pressure system which includes a compressor having suction and discharge conduits, said suction conduit being connected to said system, said device comprising a valve in said suction conduit positioned between said system and said compressor, an automatically operating pressure controller means for actuating said valve, a conduit connecting said controller means with said suction conduit at a point between said compressor and said valve so that said valve is actuated in accordance with the pressure in said suction conduit between said compressor and said valve, and additional valve means for operatively connecting said first-mentioned valve with said pressure controller.

3. A fluid pressure reducing device comprising in combination with a reduced pressure system which includes a compressor having suction and discharge conduits, said suction conduit being connected to said system, said device comprising a valve in said suction conduit positioned between said system and said compressor, an automatically operating pressure controller means for actuating said valve, a conduit connecting said controller means with said suction conduit at a point between said compressor and said valve so that said valve is actuated in accordance with the pressure in said suction conduit between said compressor and said valve, and means to unload said compressor during the starting-up period preliminary to automatic control including a by-pass connecting said discharge conduit and said suction conduit.

4. A fluid pressure reducing device comprising in combination with a reduced pressure system which includes a compressor having suction and discharge headers, a conduit connecting said system to the suction header, said device comprising an automatically operating pressure controller, conduit means connecting said pressure controller to said suction header for direct operation by the pressure within said suction header, a pressure operated valve actuated by said pressure controller positioned in said connecting conduit, valve means for operatively connecting said pressure operated valve with said controller for automatic control during reduced pressure operation, and means to unload said compressor

during the starting-up period preliminary to automatic control including a by-pass connecting the discharge header to said connecting conduit.

5. A fluid pressure reducing device comprising in combination with a reduced pressure system which includes a compressor having suction and discharge headers connected thereto, a conduit connecting said system to the suction header, said device comprising an automatically operating pressure controller, conduit means connecting said pressure controller to said suction header for direct operation by the pressure within said suction header, a pressure operated valve actuated by said pressure controller positioned within said connecting conduit, valve means for operatively connecting the pressure operated valve and said controller for automatic control during reduced pressure operation, and means to unload said compressor during the starting-up period preliminary to automatic control including a by-
